UNITED STATES PATENT OFFICE.

JOHN LANGE, OF BLOOMFIELD, NEW JERSEY, ASSIGNOR TO FYBUSH BROS., OF NEW YORK, N. Y., A COPARTNERSHIP COMPOSED OF JOSEPH FYBUSH AND SIMON FYBUSH.

DESIGN FOR A TRAVELING-BAG.

49,032.

Specification for Design.

Patented May 9, 1916.

Application filed March 3, 1916. Serial No. 82,002. Term of patent 7 years.

To all whom it may concern:

Be it known that I, JOHN LANGE, a citizen of the United States, residing at Bloomfield, in the county of Essex and State of New Jersey, have invented a new, original, and ornamental Design for Traveling-Bags, of which the following is a specification, reference being had to the accompanying drawing, forming part thereof, in which the figure is a perspective view of a bag showing my new design.

I claim:

The ornamental design for a traveling bag, as shown.

JOHN LANGE.

Witnesses:

M. F. MENCHER,
JOSEPH FYBUSH.
